UNITED STATES PATENT OFFICE

CARL F. BLEDSOE, OF CHICAGO, ILLINOIS, ASSIGNOR TO OGLE CONSTRUCTION COMPANY,
OF CHICAGO, ILLINOIS, A CORPORATION OF ILLINOIS

MATERIAL HANDLING PLANT

Application filed June 21, 1929. Serial No. 372,627.

This invention relates to a material handling plant which is primarily adapted for handling coal in connection with railway systems. The invention concerns itself primarily with the means for guiding and supporting the hoisting bucket so that it may be dumped upon the same side of the tower as the feeding hopper.

The invention comprises the novel structure and combination of parts hereinafter described and more fully and particularly pointed out and defined in the appended claims.

In the accompanying drawings which illustrate a preferred embodiment of this invention and in which similar reference numerals refer to similar features in the different views:

Figure 1 is a vertical sectional view through the hoisting tower and pit, showing parts in elevation and involving this invention.

Figure 2 is an enlarged fragmentary elevational view of a portion of the tower taken at the dumping station.

Figure 3 is a sectional view taken upon the line III—III of Figure 1.

In the drawings there is shown a vertical hoisting tower, which may be of any well-known structure. Adjacent one side of this tower there is a feeding hopper 1 which is adapted for feeding material to a hoisting bucket 2. The hoisting bucket 2 is connected by means of a pair of links 3 to a bail 4. A pair of rollers 5 is journaled upon each side of the bail 4 and these rollers are guided for traveling movement in a pair of guides 6 which are supported in the vertical tower and which extend into the pit, where the same are provided with inclined portions, which extend beneath the hopper 1. In the present instance, the guides 6 are shown in the form of channels in which the rollers 5 are adapted to fit for rolling movement.

Upon the sides of the bucket 2 are lateral rollers 7 which are mounted coaxially with the pivot point of the links 3. These rollers 7 are adapted to travel in guideways formed by one flange of the channel guides 6 and the flange of a rail 8, which extends alongside one of the channel guides 6. It will be noted that the guides formed by the channel 6 and the rails 8 are narrower in the vertical portion thereof than in the inclined portion. This is for the purpose of allowing the hoisting bucket to remain in upright position at all times. The rails 8 extend to an intermediate point in the tower, where they are curved outwardly upon that side of the tower where the hopper 1 is located. The curved portions of the rails 8 at the dumping station are united with curved pieces 9 extending from the guides 6. The curved pieces 9 extend downwardly and unite with the rails 8 to form a closed guideway to limit the outward movement of the bucket when it is being dumped. Upon the forward part of the bucket, there are journaled a pair of rollers 11, one on each side for travelling upon the track 8 and maintaining the bucket in upright position upon the inclined portions of the track. The rollers 11 are adapted to travel upon the flange of the track or rail 8 until the rollers 7 begin to travel in the curved portions of the guideway formed between the rail 8 and the guides 6.

At this point, the rollers 11 leave the track 8 and engage in anchor loops 12 which in connection with the curved portions of the guides for the buckets cause the same to revolve and dump its contents as shown in dotted lines in Figure 1. When the bucket descends, the rollers 11 will travel idly adjacent the track 8 and when the bucket reaches the inclined portions of the guides, the rollers 7 will contact the rails 8 for maintaining the bucket in upright position. To this end it will be noted that the rails

8 are spaced further from the guides 6 at the lower inclined portion thereof than at the vertical portion thereof for the purpose of allowing the bucket to swing around the 5 curve in upright position. The lower ends of the guides 6 are provided with stop abutments 13 (Figure 1) that approach the rails 8. In descending, the rollers 7 on the bucket are arrested by these abutments.

- 10 It will be appreciated that the apparatus involving this invention, supports the bucket in upright position and dumps the same from the same side of the tower as the bucket receives its load. This will make it 15 possible to coal an engine upon the tracks which pass over the hopper. It will be further appreciated that the apparatus is very simple and efficient especially from the standpoint of operation.
- 20 I am aware that numerous details of construction may be varied through a wide range without departing from the principles of this invention and I therefore do not purpose limiting the patent granted, otherwise than necessitated by the prior art.

I claim as my invention:

1. In a material handling plant, two pair of adjacent guide ways having lower inclined portions, one pair of said guideways 30 terminating at its upper end in outwardly curved portions extending in the same general direction as the lower inclined portions, a bucket having rollers traveling in the guideways having the curved terminals, 35 a bail having rollers traveling in the other guideways, links connecting said bail and bucket, rollers on the forward part of said bucket and means for guiding said last mentioned rollers.
- 40 2. In a material handling plant having a feeding hopper upon one side, a pair of opposite guides having inclined portions leading to said feeding hopper, a rail adjacent each guide and forming a guideway therewith, a bucket having rollers adapted 45 for traveling upon said rails and rollers traveling in said guideways, a bail having rollers traveling in said guides, links connecting said bail and bucket, and means 50 whereby said bucket is dumped upon the same side as said feeding hopper.
3. In a material handling plant, a pair of guides having vertical portions and downwardly inclined portions, a rail adjacent each guide and forming a guideway 55 therewith, a bail having rollers traveling in said guides, a bucket having rollers traveling upon said rails and rollers traveling in said guideways and links connecting said bail and bucket.
- 60 4. In a material handling plant, a pair of opposed channel guides having vertical portions and laterally inclined portions, a rail adjacent each guide and forming a 65 guide way therewith, a bail having rollers

travelling in said guides, a bucket having a roller travelling upon said rail and lateral rollers travelling in said guide way, links connecting said bail and bucket, said guides and rails being more widely spaced at the 70 inclined portions for maintaining said bucket in vertical position.

In testimony whereof I have hereunto subscribed my name at Chicago, Cook County, Illinois.

CARL F. BLEDSOE.
